CLAIM

The ornamental design for a deck railing section, as shown and described.

DESCRIPTION

FIG. 1 is a perspective view of the deck railing section showing my new design;

FIG. 2 is a top plan view thereof, the bottom plan view being identical thereto;

FIG. 3 is a front elevational view thereof, the rear elevational view being identical thereto; and,

FIG. 4 is an elevational view taken from the right side of FIG. 3. The left elevational view being identical thereto.
